UNITED STATES PATENT OFFICE.

EUGÈNE SCHNEIDER, OF PARIS, FRANCE, ASSIGNOR TO SCHNEIDER & CIE., OF PARIS, FRANCE, A LIMITED JOINT-STOCK COMPANY OF FRANCE.

TURBINE.

1,371,327.

Specification of Letters Patent. Patented Mar. 15, 1921.

Application filed July 21, 1920. Serial No. 397,948.

To all whom it may concern:

Be it known that I, EUGÈNE SCHNEIDER, a citizen of the Republic of France, residing at Paris, France, have invented new and useful Improvements in Turbines, which invention is fully set forth in the following specification.

When the blades A of a turbine wheel are not fixed individually to the turbine wheel 10 C, but are merely held (as shown in Figs. 1 and 2 of the accompanying drawings) by their roots B of dovetail or other shape, in a groove of corresponding section formed all around the periphery of the wheel C, it is necessary to provide at a point C¹ of said groove, for the engagement of the blades, a notch having a width equal to that of the roots of the blades. The blades B are inserted in succession through the said notch 15 and the blades are pushed into the groove, the said roots being held as shown in Fig. 2 by the engagement of their shoulders b under the ledges C¹.

By this means all the blades and their 25 spacing pieces can be inserted except one of the latter which is generally made in two parts (Fig. 2) comprising namely a main element D shaped like the root of a blade which is engaged in the groove through the 30 notches C¹ and which is then pushed so as to engage a part of the root under the ledges c¹, and a locking piece E over which the upper part of the root-shaped element D is turned down, so as to fill the gap left by 35 the notches.

The present invention has for its object 40 to improve this fastening means, especially when monoblock blades are employed, that is to say, blades formed in one piece without separate spacing pieces in between the blades.

For this purpose a plurality of blades distributed partly on one side and partly on the other side of the axis of the entry 45 notches C¹ are shaped in such a manner that their roots bear against one another by means of surfaces inclined relatively to the radii of the wheel. The filling blade then has a truncated root which is completed by the 50 usual filling piece and locking piece which engage together as a whole into a space having a trapezoidal form in longitudinal section, the long base of the trapezoid being situated on the inside. In this manner the 55 strains due to the action of centrifugal force

upon the filling pieces, are taken not only by the said pieces but also by the two terminal blades against which they bear, and if desired, also by the two blades that respectively follow and precede those first two 60 blades, or any other desired greater number of similar blades.

A practical constructional form of this invention is illustrated by way of example in the accompanying drawings. 65

Figure 1 is an axial section through the wheel between two ordinary blades;

Fig. 2 is a horizontal section of a developed section of the wheel.

Fig. 3 is a section on the line 3—3 of Fig. 70 1, of a segment of a blade wheel comprising the special blades and the two fastening pieces placed in position.

Fig. 4 is a section on the line 4—4 of Fig. 3. 75

Fig. 5 is a section on the line 5—5 of Fig. 4.

The blades A—B of the usual shape are placed in position by passing their roots through the entry notches C¹ of the wheel C. 80

In the example shown, the four blades F—G, H—I, J—K, L—M are each formed with a peculiarly shaped root, and they are designed to withstand uniform strains due to the action of centrifugal force. For this 85 purpose the roots G and M are made thinner at the base, so that the roots I and K will bear respectively with their complementary faces, i, k against the conical faces g and m of these roots. 90

On the other hand the lodgment for the filling pieces D and E has in longitudinal section the form of a trapezoid having its long base situated on the inside. It is to be understood that the roots I and K have 95 bearing surfaces i¹ and k¹ formed with a corresponding inclination.

The filling piece D has a greater thickness at its base than at its top. Moreover it has two shoulders d adapted to engage under 100 the root of the blade I in the gaps left free by the notch in the wheel.

The locking piece E is forcibly driven in between the part D and the blade K.

After the locking piece E has been placed 105 in position, the top of the part D (indicated in dot and dash lines in Figs. 3 and 5) is turned over and burred down upon the locking piece E.

With this arrangement, the effects of cen- 110

trifugal force acting upon the parts D and E, are taken by the terminal blades H—I and J—K which transmit a part of the strain to the adjacent blades F—G and 5 L—M.

It will be perceived that notwithstanding the gaps in the ledges c^1 of the groove of the wheel at the opening C¹, the fastening parts D, E and a portion of the blades H—I, 10 J—K that do not bear against the ledges c^1 of the wheel, are stayed by the wedging action of blades F—G and L—M in such a manner that the strains will be distributed uniformly on the roots of the blades G, I, 15 K, M.

It is an easy matter to arrange that a greater number of blades shall share in taking these strains by giving to their roots the special shape of the roots G and M.

20 Having now particularly described and ascertained the nature of my said invention and in what manner the same is to be performed, I declare that what I claim is:—

1. In a turbine, a wheel having a circumferential ledged groove provided with entry notches, a series of blades having shou- 25 ldered roots at their inner ends to fit the ledged groove successively introduced therein through the entry notches, the two 30 terminal blades of the series having their roots spaced apart opposite the entry notches with the opposite faces of said roots inclined toward each other to form a lodgment of trapezoidal section with its wider 35 base on the inner side thereof, and complementary filling and locking pieces forced into the lodgment to press apart the roots of the terminal blades, each terminal blade and the blade adjacent thereto having the 40 mutual contacting faces of their roots in wedging engagement against outward displacement of the terminal blade so that the roots of the two terminal blades and of the blades adjacent thereto mutually operate to 45 hold the filling and locking pieces against outward displacement through centrifugal force imparted by rotation of the wheel.

2. In a turbine, a wheel having a circumferential ledged groove provided with entry notches, a series of blades having shou- 50

dered roots at their inner ends to fit the ledged groove successively introduced therein through the entry notches, the two terminal blades of the series having their roots spaced apart opposite the entry notches with 55 the opposite faces of said roots inclined toward each other to form a lodgment of trapezoidal section with its wider base on the inner side thereof, and complementary filling and locking pieces forced into the 60 lodgment to press apart the roots of the terminal blades, each terminal blade and the blade adjacent thereto having the mutual contacting faces of their roots inclined relatively to a radial plane of the wheel to 65 taper the root of the adjacent blade toward its inner end, the terminal and adjacent blades having their roots so associated on opposite sides of the interposed filling and locking pieces operating to hold said pieces 70 against outward displacement through centrifugal force imparted by rotation of the wheel.

3. In a turbine, a wheel having a circumferential ledged groove provided with entry notches, a series of blades having shou- 75 ldered roots at their inner ends to fit the ledged groove successively introduced therein through the entry notches, the two terminal blades of the series having their roots spaced apart opposite the entry notches with 80 the opposite faces of said roots inclined toward each other to form a lodgment of trapezoidal section with its wider base on the inner side thereof, and complementary filling and locking pieces forced into the lodgment to press apart the roots of the terminal blades, the wedging action 85 of the roots of the terminal blades operating to hold the filling and locking pieces within the lodgment against outward displacement through centrifugal force imparted by rotation of the wheel. 90

In testimony whereof I have signed this specification.

EUGÈNE SCHNEIDER.
